UNITED STATES PATENT OFFICE

134,344

DESIGN FOR A JEWELRY STONE OR SIMILAR ARTICLE

Edward W. Maloney, Brooklyn, N. Y.

Application April 11, 1942, Serial No. 106,554

Term of patent 14 years

To all whom it may concern:

Be it known that I, Edward W. Maloney, a citizen of the United States of America, residing at Brooklyn, in the county of Kings, city and State of New York, and whose post-office address is 258 Eckford Street, Brooklyn, New York city, N. Y., have invented a new, original, and ornamental Design for a Jewelry Stone or Similar Article, of which the following is a specification,

reference being made to the accompanying drawing, forming a part thereof.

The figure in the drawing is a perspective view of a jewelry stone or similar article showing my new design.

I claim:

The ornamental design for a jewelry stone or similar article, substantially as shown.

EDWARD W. MALONEY.
